UNITED STATES PATENT OFFICE.

HARRY L. STRAND, OF BOSTON, MASSACHUSETTS, ASSIGNOR OF ONE-HALF TO LEO F. EMERSON, OF BROOKLINE, MASSACHUSETTS.

BUILDING BLOCK AND WALL.

Application filed July 15, 1925. Serial No. 43,839.

This invention relates to building blocks and wall construction, and particularly to terra cotta or hollow tile building blocks used especially in backings for brick walls or 5 veneers. An object of the invention is to provide an improved building block which will be more economical in use, will be capable of a greater variety of uses under differing conditions, and wherein walls constructed in part with said blocks will not only be cheaper to build but structurally stronger in the requisite directions.

Building blocks as heretofore constructed have been capable only of limited use because 15 they have not had equal or substantially equal structural strength when placed in different positions or when subjected to load for a portion only of their surface area. Furthermore, as is well-known to those skilled in the 20 art, terra cotta blocks have varied considerably in dimensions as a result of differences in burning. Blocks placed close to the fire and known to the trade as hard burned tile contract more than blocks placed at a distance from the fire, these latter blocks being 25 known as light burned tile. These differences in the burning of the tile have resulted in differences of dimensions. When a course of tile is being laid, a light burned tile will 30 stick up above the other tiles in the course or project beyond them and it has been necessary to compensate in some way for the differences in dimensions. This has been done by rejecting the tile or by trimming it off or 35 by filling up the differences with mortar. The building block embodying my present invention obviates these difficulties and is so constructed that a light burned tile may be used in the same course with hard burned tile 40 without resorting to any of the expedients mentioned and without increasing the expense or delay.

The invention will be fully understood 45 from the following description when taken in connection with the accompanying drawings, and the novel features thereof will be pointed out and clearly defined in the claims at the close of this specification.

In the drawings:

Fig. 1 is a vertical section of a wall composed of building blocks and brick, the building blocks and filler blocks being constructed according to the invention.

Fig. 2 is a section on line 2—2, Fig. 1.

Fig. 3 is a perspective view of one of the 55 building blocks.

Fig. 4 is a view in perspective of a T-shaped filler block.

Fig. 5 is a view in perspective of a plain 60 filler block.

Fig. 6 is a perspective view of a double filler block.

Fig. 7 is a diagram illustrating the method of using my improved building block when there are variations in dimensions due to difference in burning.

Fig. 8 is a vertical section of the thin wall in which building blocks are placed with the air passages in vertical position.

Fig. 9 is a vertical section of a thick wall in 70 which the blocks are placed with the air passages in vertical position.

Fig. 10 is a vertical section of another thick wall.

It will be understood that the drawings 75 merely illustrate the commonest combinations produced by the use of building blocks embodying my present invention and that other combinations are possible.

Referring to the drawings and particularly to Fig. 3, there is there shown a building block having four large air passages *a* therethrough and two small central passages *b*, *b*. The several passages are separated from each other by vertical webs *c* and *d* and a horizontal web *e*. The dimensions of the block as I actually construct it are $12\frac{1}{2} \times 11\frac{7}{8} \times 7\frac{1}{2}$ inches but these dimensions are given merely to show the convenient proportions based on the prevailing size of brick and it will be understood that I do not limit myself to these dimensions, the essential being that two of the dimensions shall closely approximate each other but shall not be the same. Thus in manufacturing the block I prefer to have 95 the two dimensions of the approximately

square wall twelve inches plus and minus an amount sufficient to allow for variations in burning. The exterior of the block has four solid faces *f*, *g*, *h* and *i* and two open faces. 5 Two of the solid faces, namely *f* and *h*, are substantially square, while the other two solid faces *g* and *i* are rectangles. The open faces are also rectangles. It will be seen that the block is regular in shape there being no non-symmetrical projections. The exterior of 10 the solid faces of the block is preferably provided with dovetail grooves *k*, as shown in the drawings to interlock with the mortar.

In Fig. 4 there is shown a T-shaped filler block 90 which is conveniently used in combination with the building blocks already described particularly when a veneer brick face is employed, the header course of which is of Flemish bond. In Fig. 5 I have shown 20 a straight filler block 13 of rectangular cross section. This block is convenient for filling in places at the rear of the header courses and spaces in the walls. It can be used in vertical or horizontal position as required and 25 for pipe chases and the like.

In Fig. 6 there is shown a double filler block 30 which is convenient for use in thick walls. It contains three longitudinal passages *K*, *L* and *M* and is constructed so that 30 it can be broken apart along the line *o*—*o* to form two single filler blocks if desired.

In one type of wall such, for instance, as shown in Fig. 1, the building blocks are placed in a horizontal position, that is, with the 35 air passages running horizontally and the substantially square solid surfaces parallel with the face of the wall. Such a block is indicated at 12 in Fig. 1. It rests on a header course of brick 14 and the filler block 13. Resting on the header course are five courses 40 of brick 15 the top of which is level with the top of the building block 12. On top again of the block 12 of the face courses 15 is another header course 14 and filler block 13. 45 There is preferably left an air space 16 between the rear of the face courses and the front of the block 12. At 17 I have shown a floor beam resting on the top of one of the blocks 12.

50 It will be seen that the rear end of the bricks forming the header course are supported on two webs *c* and *f* of the building block while the load imposed by the floor beam is supported by the three webs *c*, *d* and *h*. By this 55 arrangement the loads are thoroughly supported and properly distributed.

I will now describe typical walls embodying my invention, referring first to Figs. 1, 2 and 7. In this wall there is a front veneer 60 of brick, there being five courses 15 between the header courses 14. The header courses 14 are laid in Flemish bond, as shown in Fig. 2. The courses of building blocks in this wall are normally laid with the air passages 65 running horizontally and the substantially

square solid surfaces parallel with the face of the wall. Such a block is designated 12 in Fig. 1. It rests on the header course of brick 14 and the filler block 13. The five courses of brick 15 are separated from the 70 building block by an air space 16. This construction is continued throughout the wall. At 17 I have shown a floor beam resting on the top of one of the blocks 12. It will be seen that the rear end of the bricks forming 75 the header course are supported by two webs of the building block while the floor beam is supported on three webs, it being understood of course that the rear end of the header brick opposite the end of the floor beam is broken 80 away.

At 40 is shown one building block with its air passages in the vertical instead of the horizontal position. This is intended to represent a light burned tile. The diagram 85 shown in Fig. 7 illustrates the method of procedure when such a burned tile is encountered by the workman. It is assumed that the tiles in the course are being laid as shown at 41 and 42 with the air passages horizontal and their longest dimension in vertical position. Let it be assumed that having laid the tile 41, the workman encounters the tile 40 which is light burned and therefore when put in place sticks up above the neighboring tile 41, as indicated at 43 in dotted lines. Heretofore, under these conditions it has been necessary for the workman to reject the tile or else resort to some expedient such as cutting off the top of the tile or bringing the 90 adjacent tiles up to the level by the use of additional mortar. With the tile embodying my invention the workman turns the tile over 90° thus bringing its short dimension into vertical position and its long dimension 105 into horizontal position. Its top will then be slightly either below the top of the adjacent tiles or approximately on a level therewith. In the former case this is usually compensated for by mortar since only one tile 110 requires to be built up instead of the entire course. When turned in this manner the tile may crowd the next tile 42 along slightly but this is readily taken care of by reducing the mortar between successive tiles or at the end 115 of the course.

In practice, this difference horizontally in the wall causes no serious difficulty although the same variation or difference vertically in the wall has heretofore caused a great deal 120 of difficulty and unnecessary expense on account of the practice of workmen in shattering and trimming off the tops of blocks.

The spaces beyond the header courses are filled with filler blocks, as for instance, a 125 T-shaped filler block 90 shown in Fig. 4, where the header course is of Flemish bond or single filler block 13 shown in Fig. 5 where a simple header course is employed.

Referring now to Fig. 8 there is shown a 130

wall in which the building blocks 12 are placed on their end, that is, with the air passages in vertical position. This wall is constructed like the wall already described and 5 it will be seen that the floor beam 17 is supported on three vertical webs *c*, *d* and *h*, while the header courses between the floor beams are supported on two webs *e* and *f*.

In Fig. 9 there is shown a wall in which the 10 building blocks 12 are placed on end as in Fig. 8 but with the substantially square solid surfaces *f* and *h* at right angles to the face of the wall. This construction affords a relatively thick wall in which the floor beams 15 are supported by the webs *e* and *g*. In this case the building block rests on a header course of brick 14 and two filler blocks 13, or on a double filler block 30 as shown in Fig. 6.

20 In Fig. 10 is shown a vertical section of a relatively thick wall in which the building blocks are laid with the air passages running horizontally but with the substantially square solid surfaces at right angles to the 25 face of the wall. Between the header courses 14 in this type of wall one whole block and a portion of a block are employed. Such a portion is indicated at *B* and is obtained by severing the block 12 on the plane *X*—*X* in Fig. 30 2. In this case a filler block 30 constructed as shown in Fig. 6 is employed at the rear of the header course 14. This filler block is formed with a groove on the top and bottom surfaces and located centrally thereof where- 35 by the block may be broken and only a portion of it used to fill small spaces or to provide for pipe chases. The broken portion may also be used as a filler for the thin wall shown in Figs. 1, 8 and 9.

40 The foregoing walls are typical but it will be understood that it is not necessary to have all the building blocks in a wall vertical or horizontal but that various combinations and arrangements may be made, those shown in 45 Figs. 1, 8, 9 and 10 of the drawings being merely typical arrangements.

The building block embodying my invention is adapted for use in a wall as a backing for a predetermined number of superimposed bonded face courses of brick, such as five 50 courses. The block has an approximately square face or wall, the required dimensions of which are determined by the known height of the bonded face courses. In its manufacture the block is pre-formed with one edge of the square face or wall a predetermined amount shorter than the other edge of the square wall at right angles thereto, so that irrespective of whether the block turns out 55 to be hard burned or light burned, one of said edges will, after burning, have substantially no greater length than the required square dimension whenever the length of the other edge is substantially greater, or is such as to

cause the block to project a substantial distance above the top of the face courses. 65

What I claim is:

1. A wall construction comprising a brick facing composed of superimposed face courses of brick, a hollow building block forming a 70 backing for said face courses, a header course of brick supported directly in part on said block, and a filler block in rear of the header course and supported on said building block, the latter having a pair of vertical webs sup- 75 porting the filler block and spaced substantially the width of a pair of opposite walls of the filler block.

2. A tile building block adapted for use in a wall as a backing for a pre-determined number of superimposed bonded face courses of brick and formed with an approximately square wall of required dimensions to conform to said face courses, said block being pre-formed with one edge of the square wall a 80 predetermined amount shorter than the other edge at right angles thereto to provide, when either light burned or hard burned, one of said edges with substantially no greater height than the said required square dimensions when the block, if turned at right angles, 85 projects a substantial distance above the top of the face courses.

3. In a wall construction, a plurality of superimposed bonded face courses of brick, a 90 tile block supported in rear of said face courses and having an approximately square wall of required dimension to extend flush with the top and bottom of said face courses, said block having the sides of the square wall 100 at right angles to each other preformed with different dimensions and whether light or hard burned, having one of said sides, when extending vertically in the wall, substantially no greater in height than the height of 105 said face courses when the block, if turned at right angles, projects a substantial distance above the top of the face courses.

4. In a wall construction, a plurality of superimposed bonded face courses of brick, a 110 plurality of tile building blocks supported side by side in rear of said face courses, and each having an approximately square wall parallel to and of approximately the height of the brick face courses, each tile block being pre- 115 formed with one edge of the square wall substantially no greater than the height of the face courses whenever the other edge of the square wall exceeds said height on account of variations in burning of the blocks, whereby 120 the block may be positioned with the shorter edge of the square wall extending vertically when the block, if turned at right angles, projects a substantial distance above the top of the face courses.

5. A wall construction comprising a brick facing composed of superimposed bonded face courses of brick, a hollow tile building

- block forming a backing for said face courses and having four vertical webs parallel to the face of the wall, a header course of brick supported in part on said block and in part on the 5 face courses, a filler block in rear of the header course and supported on said building block, the latter having a pair of said vertical webs

substantially aligned with a pair of opposite vertical walls of the filler block, and also having another pair of vertical webs supporting the brick header course. ¹⁰

In testimony whereof I affix my signature.

HARRY L. STRAND.
